Des. 216,495
Patented Jan. 13, 1970

216,495

BLENDER BASE

Morison S. Cousins, Plainview, N.Y., assignor to Dynamics Corporation of America, New York, N.Y., a corporation of New York

Filed May 31, 1968, Ser No. 12,166

Term of patent 14 years

Int. Cl. D7—05

U.S. Cl. D89—1

FIG. 1.

FIG. 2.

Des. 216,495

PAGE 2

FIG. 3.

FIG. 4.

FIG. 5.FIG. 1 is a perspective view of a blender base showing my new design;

FIG. 2 is a side elevational view, it being understood that the opposite side view is a mirror image of the same;

FIG. 3 is a front view;

FIG. 4 is a top view; and

FIG. 5 is a rear view.

I claim:

The ornamental design for a blender base, as shown and described.
